ATTORNEY

UNITED STATES PATENT OFFICE.

A. CLARKE TONNER, OF CANTON, OHIO.

BURGLAR-ALARM.

SPECIFICATION forming part of Letters Patent No. 318,834, dated May 26, 1885.

Application filed October 20, 1884. (Model.)

To all whom it may concern:

Be it known that I, A. CLARKE TONNER, a citizen of the United States, residing at Canton, in the county of Stark and State of Ohio, 5 have invented certain new and useful Improvements in Burglar-Alarms; and I do hereby declare that the following is a full, clear, and exact description of the same, reference being had to the annexed drawings, making a part 10 of this specification, and to the letters and figures of reference marked thereon, in which—

Figure 1 is a top view, showing the alarm placed in proper position and set ready for an alarm. Fig. 2 is a top view showing the 15 alarm sprung. Fig. 3 is a transverse section on line $x-x$, Fig. 1. Fig. 4 is a detached view of the wheel and ratchet. Fig. 5 is a top view showing part of the bell and spider-plate broken away.

20 The present invention has relation to that class of burglar-alarms designed to be temporarily attached to a door or other place designed to be used; and its nature consists in the different parts and combinations of parts 25 hereinafter described, and pointed out in the claims.

Similar letters of reference indicate corresponding parts in all the figures of the drawings.

30 In the accompanying drawings, A represents the base-plate, which is substantially of the form shown in Fig. 5. This plate A is provided with the extensions or arms B and C. To the plate A is attached the spider-plate or 35 cap D, the locking-slide E, and the locking-lever F, substantially as shown in the drawings.

The outer end of the arm B is bent, as shown in Fig. 3, and is provided with the desired 40 number of piercing-points a . This bent or curved portion of the arm B is formed thin, so as not to interfere with the closing of a door when the alarm is placed in proper position.

The arm C is provided with the hinged cap 45 G, which is substantially of the form shown in the drawings. The hinged cap G is provided with the desired number of piercing-points b . These piercing-points b are inclined toward the arm B, so that they will cause the 50 points a to be forced into the door-casing as the cap G is forced downward, thereby holding the alarm in proper position.

The post H is substantially of the form shown in Fig. 3, and turns in suitable bearings in the base-plate A and the spider-cap 55 D. To this post is rigidly attached the ratchet-wheel I, which is of the form shown in Fig. 4. On the post H is loosely placed the wheel J, which is of the form shown in Fig. 4. To this wheel J is attached the spring-dog 60 K, which engages the ratchet-wheel I, as seen in said Fig. 4.

The escapement d is located as seen in Fig. 5, and is so arranged that it will engage the teeth of the wheel J. To the escapement is 65 rigidly attached the hammer-arm e, said arm being bent or curved, as shown in the drawings. To this hammer-arm is attached the hammer f, as shown.

The locking-slide E is forked at one end, as 70 shown, and in said fork fits a pin, i, secured to base-plate A, and also is provided with the pin g, which is for the purpose of pressing on the hammer-arm e, and thereby locking the escapement when said slide E is pressed inward by means of the locking-lever F.

To the arm B is attached the hinged cap L, which is substantially of the form shown in the drawings. This hinged cap L is provided with the recess h, which receives the outer 80 end of the locking-slide E, as seen in Fig. 5.

The bell M is substantially of the form shown in the drawings, and is rigidly attached to the spider-plate D, and is so arranged that the hammer will strike said bell as the alarm is 85 running down, motion being communicated to the hammer by means of the spring N, said spring N being attached at one end to the winding-post H, the opposite end being attached to one of the arms of the spider-plate D. 90

In use the locking-lever F is placed in the position indicated by the dotted lines in Fig. 5, so as to bring its heel against the slide E, and thus prevent the latter from moving. The spring N is then wound by turning the post 95 H, and the alarm placed on the door-casing, as seen in Figs. 1 and 2, when the door is closed, and the hinged cap L placed in the position shown in Fig. 1, with the end of slide E fitting against the walls of slot h, so that the 100 slide cannot move, when the locking-lever is placed as shown in Figs. 1, 2, and 5, so as to remove its heel from contact with the slide. The alarm is now set. Now, when the door is

opened the hinged plate L is thrown back into the position shown in Fig. 2, so as to be free from contact with end of slide E, and then the influence of spring N on the post H will cause 5 the latter to revolve and carry with it the wheel J, so as to move it from binding contact with the escapement d. The latter being released and caused to oscillate, by the teeth of the wheel striking against it, motion is im- 10 parted from it to the arm e, so as to cause the hammer f to strike the gong M and sound the alarm until the spring loses its power, the lug or slot g being moved with the slide E, so as not to bind against the arm e.

15 Having now fully described my invention, what I claim as new, and desire to secure by Letters Patent, is—

1. In an alarm, the combination, with a base-plate, gong, hammer, escapement mechanism, 20 and spring for actuating the same, of a slide, E, adapted to bear against the arm of the hammer, a lever adapted to be brought against said slide to hold it against the hammer-arm, and a hinged plate adapted when in one posi- 25 tion to hold said slide against movement, and then in another position to release it, substantially as described.

2. In an alarm, the combination of a base-plate provided at one point with a bent spur-arm, and at another with a hinged spur-arm, a gong, hammer, escapement mechanism, and spring for actuating the same, a slide, E, operating to control the movement of the hammer, a pivoted lever, F, for locking said slide, and a hinged plate, L, formed with a slot 35 adapted when in one position to fit about the end of the slide E, to hold it, and when in another position to release it, substantially as described.

3. The combination, with base-plate A, spi- 40 der D, and gong M, of the winding-post H, toothed disks I and J, and spring N, connected with said post, escapement d, and hammer e f, slide E, lever F, and the hinged slotted plate L, the several parts adapted to operate sub- 45 substantially as described.

In testimony that I claim the above I have hereunto subscribed my name in the presence of two witnesses.

A. CLARKE TONNER.
